A. R. POOLE

KNITTED CAP

Filed Oct. 11, 1924

Inventor

Amos R. Poole

By his Attorney, Howard W. Dix

UNITED STATES PATENT OFFICE.

AMOS R. POOLE, OF NEW YORK, N. Y.

DESIGN FOR A KNITTED CAP.

Application filed October 11, 1924. Serial No. 11,047. Term of patent 7 years.

To all whom it may concern:

Be it known that I, AMOS R. POOLE, a citizen of the United States, residing at New York city, New York, have invented a new, original, and ornamental Design for Knitted Cap, of which the following is a specification, reference being had to the accompanying drawing, forming part thereof.

The figure is a perspective view of a knitted cap, showing my new design.

I claim:

The ornamental design for a knitted cap, as shown.

AMOS R. POOLE.
